UNITED STATES PATENT OFFICE.

SAMUEL GOODFRIEND, OF PHILADELPHIA, PENNSYLVANIA.

COAT-FORM IMPROVER.

No. 893,622.

Specification of Letters Patent.

Patented July 21, 1908.

Application filed October 7, 1907. Serial No. 396,171.

To all whom it may concern:

Be it known that I, SAMUEL GOODFRIEND, a citizen of the United States, residing at Philadelphia, in the county of Philadelphia 5 and State of Pennsylvania, have invented a new and useful Improvement in Coat-Form Improvers, of which the following is a specification.

This invention relates to improvements in means for maintaining coats, cloaks and similar garments in correct shapes, and its objects are: to provide means whereby such articles of wearing apparel are caused to keep smooth, retaining their original shape, 10 particularly in the back under the collar and are prevented from wrinkling, creasing or becoming unsightly by reason of usage. To provide such means, in forms applicable to like garments, which shall be light, durable, 15 flexible, imperceptible while in use and inexpensive to manufacture. These and other minor objects are attained by the novel construction and combination of parts hereinafter fully described and shown in the accompanying drawings, forming part of these specifications, and in which have been used similar characters of reference on all similar parts throughout.

Figure 1, is a partial rear view of a coat having the form improvement applied. Fig. 2, 20 is a side elevation of the same. Fig. 3, is a developed plan view of the improver drawn to an enlarged scale, and Fig. 4, is a sectional view taken on line *a—a* of Fig. 3.

In the drawings 1, represents the back of a coat, 2, the sleeves, 3 the collar, and 4, the lapels, all of which may be made in any cut or style preferred and in the usual manner.

At the back of the garment, immediately 25 below the collar and extending from one shoulder to the other, is disposed the improver, attached along its upper edges and at the ends to the seams of the garment, between the lining and outer material, or, if no lining be used, to the inside of the garment. The attaching means may consist of stitching the improver in place or in any other satisfactory method whereby the bound edge is secured, but preferably in such manner that 30 the improver can be removed and used again in other garments should it be desired.

The improver comprises a central web of hair cloth, or an equivalent, resilient stiffening material 5, not affected by the weather, 35 temperature conditions or moisture, as from perspiration of the wearer, the same being

inclosed between sheets of closely woven textile fabrics, 6, as silesia, canvas or the like, and bound about the edge with tape 7, the several thicknesses or layers being quilted as 60 at 8, to obviate the shifting of one relative to the others and also to maintain the hair cloth in position and prevent the same from working through any part of the garment.

In regard to the exact form or shape of my 65 article, it will be noted that the opposite side edges of the same are curved inwardly, while the lower edge is bellied or curved outwardly, or downwardly. Furthermore the curve of each side edge is sharper near the upper or 70 collar edge, this being desirable in order that the upper portion of the improver may conform properly with the shape of the collar 3 of the coat, and thereby accomplish the desired result of stiffening the collar and preventing the wrinkling of the back portion of 75 the garment adjacent thereto. The upper edge of the appliance also curves inwardly, and the curvature of the opposite side edges is such that the article is provided with two 80 points 9, which in the use of the improver, are fastened to the garment near the shoulder seams, and those seams connecting the sleeve with the shoulder portions of the coat.

While this device in no wise interferes with 85 the roll of the collar or fit of the garment, it does effectually prevent the unsightly breaking or wrinkling in the back, below the collar and which frequently occurs in the highest grade of goods, made in the most perfect 90 manner, when the garments are worn by the majority of people.

The use of this device not only simplifies making and maintaining well fitting garments but avoids the use of padding or stays, 95 which are sometimes resorted to in order to obtain satisfactory results.

The effect of the hair cloth or its equivalent, is to maintain the collar by affording a support to it, and at the same time keep the 100 goods pressed smoothly outward, sustaining that part of the garment which otherwise is liable to break into unsightly creases in conforming to the shape of the wearer, there being no support at the point of application 105 of this device; the enveloping fabrics are mainly to prevent any loose ends of the horse hair from protruding and piercing the garment or annoying the wearer.

Obviously the improver is so light in weight 110 as to be unnoticed by the wearer and no discomfort is felt from the slight addition in

thickness of the garment; its presence cannot be detected by observation, except it be surmised from the perfect symmetrical shape, smoothness and hang of the garment.

5 It will be understood that I reserve the privilege of modifying the improver from the exact shape illustrated, and may also construct the same of any suitable material, besides those mentioned herein, and I may 10 make use of several layers of material in heavy weight garments without departing from the general spirit of the invention.

Having thus described the same, what I claim as new and desire to secure by Letters 15 Patent, is:

In combination, a garment provided with a collar, a form improver therefor comprising a body composed of stiffening material such as hair-cloth, and layers of silesia between 20 which the hair-cloth is arranged, said body

being located transversely of the upper back portion of the garment and being reduced in width at its upper end and wide at its lower end the upper reduced end of the body being arranged beneath and secured to the collar 25 portion of the garment, while the opposite side portions of the body terminate in pointed members extending to the shoulder portions of the garment and being secured thereto near the shoulder seams, whereby the upper 30 back portion of the garment is preserved in flat or unwrinkled condition.

In testimony whereof I, have hereunto signed my name to this specification in the presence of two subscribing witnesses.

SAMUEL GOODFRIEND.
